(57) CLAIM

The ornamental design for a work lamp, as shown and described.

DESCRIPTION

FIG. 1 is a perspective view of a work lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof in a first condition; and,

FIG. 9 is another perspective view thereof in a second condition.

The dashed broken lines illustrate portions of the work lamp and form no part of the claimed design.
